GRADE INDICATOR FOR TRENCHING MACHINES

William G. Van Voorhis, Findlay, Ohio, assignor
to The Buckeye Traction Ditcher Company,
Findlay, Ohio, a corporation of Ohio

Application September 25, 1942, Serial No. 459,632

9 Claims. (Cl. 33—185)

This invention relates to excavating machines but more particularly to wheel type excavating machines which are equipped with an excavating wheel having a series of excavating buckets disposed at the rear of the machine. The invention is primarily concerned with grade indicators for machines of this character for enabling the operator to maintain the desired grade in the excavated trench or ditch, this being particularly necessary in the excavating of tile receiving trenches.

Heretofore excavating machines of the above character have been equipped with grade indicators in the form of sight rods carried by the digging wheel frame at the rear of the machine. In one case the operator was located at the rear end of the machine in order to observe the sight rod but this has proved objectionable because of the complicated controls which are necessary. One set of controls was arranged in the normal position intermediate the front and rear ends of the main frame and a duplicate set of controls was arranged at the rear of the machine in the position occupied by the operator during the digging operation. Obviously this not only added substantial expense to the machine but also reduced the efficiency of the operation and was somewhat unsightly.

Another method used heretofore was to arrange the grade stakes at the rear of the machine, the operator occupying the normal driving position intermediate the front and rear ends of the machine. However, in this case the operator must not only watch rearwardly to keep the sight rod aligned with the grade stakes but must also keep watch ahead to prevent the machine from advancing transversely out of the intended line of travel. Manifestly considerable difficulty was involved in keeping watch continuously in both directions.

Objects of this invention are to overcome objections inherent in the prior methods above mentioned; to produce a sight rod arrangement for wheel type excavating machines which is convenient to the operator in the normal operating position of the machine sufficiently forward thereof to afford greater vision ahead while also enabling him to observe and control the digging operation readily and conveniently, thereby requiring but a single set of controls; to produce a sight rod for such machines which is automatically responsive to vertical movement of the front end of the machine for compensating for such movement without substantial alteration to the initial setting of the sight rod; to enable

convenient manual adjustment of the sight rod to enable it properly to be aligned with a particular grade stake; and to produce a sight rod structure arrangement having the new and improved features of construction and arrangement hereinafter described.

For purposes of illustration but not of limitation, an embodiment of the invention is shown on the accompanying drawings in which

Figure 1 is a side elevation of a wheel type ditching or trenching machine, parts of the operating mechanism of the machine being omitted for purposes of clarity but sufficient structure being shown to illustrate the grade indicator, the dotted line position showing the position of the parts when the front wheels encounter a bump in the surface of the ground over which the machine is travelling;

Figure 2 is a diagrammatic view of the grade indicating mechanism showing the grade indicator and cable connections between it and the digging wheel frame; and

Figure 3 is a view similar to Figure 1 indicating by broken lines the position of the parts when the front wheels of the machine encounter a depression in the ground surface.

The illustrated embodiment of the invention comprises a wheel type excavator having a main frame 10, the front end of which is supported by a pair of rubber tired wheels 11, the rear end of which is supported by sets of tandem rubber tired wheels 12. Fixed to the rear end of the main frame 10 is a pair of laterally spaced upright beams or elevator rails 13 on the upper ends of which is a sheave arrangement 14 over which cables pass to a digging frame 15. The forward end of the cables are suitably connected to winches 16 as will be readily understood by those skilled in this art. Suitably carried by the digging frame 15 is a digging wheel 17 equipped with a series of spaced excavating buckets 18. Digging wheels of this character are well-known in the art so that more detail description is not considered necessary. It is to be understood that during the digging or excavating operation, the digging wheel frame 15 is supported in the trench in a well-known manner by a shoe or runner, which rides along the bottom of the trench, such as shown in the patent to Krupp 1,081,454, dated December 16, 1913, and also by the front cables, the cables leading to the rear portion of the digging frame being slack. Thus, it will be manifest that the digging frame 15 maintains a relation approximately parallel with the ground line during the excavating operation.

Power for the machine is furnished by a motor indicated at 19 arranged at the forward end of the machine, counterbalancing the weight of the digging wheel and its frame and also furnishing power to propel the machine, operate the digging wheel, winches, etc. The driving or operating connections between the motor 19 and their various parts are not shown since they form no part of the present invention.

Disposed in the rearward portion of the frame 10 is the operator's seat 20 directly in rear of the steering wheel 21 in front of which is arranged the usual instrument panel 22. The operator's seat 20 is conveniently disposed to the various controls such as the control levers for operating the digging wheel 17, for the winch 16, for raising or lowering the digging wheel, and for propelling the vehicle.

It will be observed that a portion of the digging wheel frame 15 extends forwardly to the upright beams or elevators 13 where it connects to slides 23 which ride vertically upon the rear portion of the beams. Only a single elevator rail 13 and slide 23 is shown since such disclosure is sufficient for a full understanding of this invention. Thus as will be readily apparent to those skilled in this art, the digging wheel 17 may be raised to travelling position when the machine is taken to or from the place of operation or can be lowered to any desired extent within certain limitations into the ground during the trench or ditch excavating operations.

The grade indicator 24 is mounted in front of the operator's seat 20 in position conveniently to be observed by the operator. As shown the indicator or sight rod 24 is in the form of an inverted L so that the upper or horizontal portion of the sight rod can be viewed by the operator and must be in alignment with the cross arms of the grade stakes as will readily be understood. These stakes are preliminarily arranged in the ground and indicate to the operator the grade to be established for the ditch or trench. The vertically disposed portion of the sight rod 24 is adjustably connected by a suitable clamp 25 to a strand 26 of cable, the upper portion of which passes about a sheave 27 mounted on the instrument panel carrying support, and the lower portion of which passes about a sheave 28 suitably mounted on the frame. Extending downwardly from the sheave 27 is a cable strand 29 which passes about a sheave 30 also carried by the frame; thence extends rearwardly providing a strand 31 to a sheave 32 mounted on the lower portion of the upright beam or elevator rail 13. From the sheave 32 the cable extends upwardly to a sheave 33 which is carried by an upwardly extending bracket arm 34 which is fixed to and movable with the slide 23. From the sheave 33 the cable extends rearwardly in a substantially horizontal direction providing the strand 34' which passes about a sheave 35 carried by a bracket 36 fixed to the forward portion of the digging wheel frame 15. From the sheave 35 the cable extends forwardly providing a strand 37 to a sheave 38 also mounted on the upper end of the slide-supported arm 34.

The cable passes around the sheave 38 and extends rearwardly thereof forming the strand 39 the end portion of which is anchored at 40 to the bracket 36. The opposite end of the cable is anchored at 41 to the upper end of the bracket arm 34 and extends upwardly to a sheave 42 which is secured to the elevator rail 13 near the upper end thereof. The cable from the sheave

42 extends downwardly providing the strand 43 to a sheave 44 which is also carried by the elevator rail 13 and at a position slightly above the sheave 32. From the sheave 44 the cable leads 5 forwardly to the sheave 28 but interposed in this strand is a helical coil spring 45 which is for the purpose of keeping the cable taut.

In use, the operator first lowers the excavating wheel to the proper depth and adjusts the sight rod 24 so that the upper or horizontal portion thereof is aligned with the cross arm on the first grade stake as will be readily understood. Then as digging progresses, the operator by means of control lever which is convenient to the operator's seat, gradually lowers or raises the digging wheel so as to excavate a deeper or shallower ditch or trench as governed by the grade stakes. It will be apparent from an inspection of the drawings that the operator is in a position conveniently not only to view the sight rod but also accessible to the control levers so that the adjustment of the digging wheel can be readily and conveniently effected. As the digging wheel is moved vertically either upwardly or downwardly, this change is correspondingly reflected in the movement either upwardly or downwardly of the sight rod 24.

It will be manifest that as the digging wheel moves downwardly the slide 23 and digging wheel frame 15 also move downwardly and such movement causes movement to the cable imparting a downward movement to the sight rod. More specifically downward movement of the slide 23 and the digging frame 15 cause the sheaves 33 and 38 on the bracket arm 34 to move downwardly. Likewise the sheave 35 on the bracket arm 36 moves downwardly. This movement decreases the length of the strand between the sheave 32 and the bracket arm carrying sheave 33 and through the cable arrangement above described, the sight rod 24 is moved accordingly, the dead end 41 of the cable imparting a pull on the cable strands passing about the sheaves 42, 44 and 28 causing the sight rod 24 to be moved downwardly a distance corresponding to the downward movement of the sheave 33 with respect to the sheave 32. Likewise any upward movement of the slide 23 which causes the lengthening of the cable strand between the sheaves 33 and 32 causes corresponding upward movement of the sight rod 24 as will be readily understood. In brief, it will be understood that the sight rod 24 moves upwardly or downwardly and in the same direction and to the same extent as the slide 23 so that at all times the operator is able to look at the sight rod to determine the operating position of the digging wheel.

Unless some means is provided to compensate for movement of the front end portion of the machine when a bump or depression of the ground surface is encountered, it will be manifest that the sight rod 24 will be inaccurate. This is depicted in the case of a bump or raised portion of the surface on Figure 1 in which condition the machine frame assumes an angular position with the front end elevated somewhat so that with the sight rod 24 remaining in the previous position, the operator would look along the line E whereas the correct line of sight is indicated by the line C. Similarly as depicted in Figure 3, when the front wheels of the machine encounter a depression, the operator would be viewing the sight rod along the line E' assuming that the sight rod remained in its previous position whereas 75 in such a condition the correct line of sight should

be along the line C'. Such change in angular position of the machine is compensated for in the above described cable arrangement.

Specifically the strands 34', 37 and 39 act as a compensator. As above explained, one end of the cable is anchored at 40 to the bracket arm 36 and from the anchorage 40, the cable passes back and forth about the sheaves 38, 35 and 33 so that upon upward movement of the front wheels 11 of the machine, the elevator rails or upright beams 13 incline rearwardly, for example, to the broken line position 13a. Since the digging frame 15 remains in a substantially horizontal position during excavation, such angular movement of the elevator rails causes the sheaves 38 and 33 to move closer to the sheave 35 and shorten the length of the strands between these sheaves. Since the cable is kept taut by the coil spring 45, the slack in the compensator strands is taken up by the strands passing about the sheaves 32, 30 and 27 causing the strand 26 to move downwardly and thereby moving the sight rod 24 downwardly. Similarly it will be manifest from an inspection of Figure 3 that when the front wheels 11 enter a depression or hollow in the road surface, the elevator rails 13 incline forwardly, for example, to the position indicated by the broken line 13b thereby lengthening the compensator strands and causing the sight rod 24 to move upwardly. Such compensating movement of the sight rod 24 is controlled in such way that upward and downward movements of the front wheels do not affect the position of the sight rod relative to the ground surface to any appreciable extent.

From the above description, it will be understood that the grade indicator or sight rod is conveniently positioned to the operator so that the necessity of having duplicate sets of controls at the rear of the machine is obviated. The operator is located in the most desirable position for efficient operation of the machine both from the standpoint of observing the digging operation, controlling the advancing movement of the machine and controlling the depth of the cut made by the excavating wheel. In the operation of the machine over uneven terrain, the sight rod at all times indicates the position of the digging wheel in spite of upward or downward movement of the front end of the machine. This latter feature is of particular importance in accurately digging a trench of the desired grade. It is manifest that the above described device can be used to advantage on machines other than rubber tired machines, as for example, machines equipped with half length crawlers and any type of round front wheels.

It is to be understood that numerous changes in details of construction, arrangement and operation may be effected without departing from the spirit of the invention especially as defined in the appended claims.

What I claim is:

1. In a ditching machine having a main frame and a digging wheel at one end thereof provided with a series of excavating buckets and a digging wheel frame mounted for vertical adjustments on the main frame, thereby to excavate at different depths, a vertically movable grade indicator on the main frame, and means including a cable and sheave arrangement providing an operative connection between the grade indicator and the digging wheel frame for causing the indicator to move upwardly or downwardly in the

same direction and to the same extent as the digging wheel frame.

2. In a wheel mounted ditching machine as claimed in claim 1 characterized in that the grade indicator comprises a sight rod, and means for adjustably fastening the sight rod to a cable strand.

10 3. In a wheel mounted ditching machine having a main frame and a digging wheel at one end thereof provided with a series of excavating buckets and a digging wheel frame mounted for vertical adjustments on the main frame, thereby to excavate at different depths, a vertically movable grade indicator on the main frame, and means providing an operative connection between the grade indicator and the digging wheel frame for imparting movements to said indicator corresponding to vertical movements of the digging wheel frame, said means including a device for causing movement of the grade indicator to compensate for angular movement of the front end of the machine due to the front wheels encountering raised or depressed ground conditions.

25 4. In a ditching machine having a main frame and a digging wheel at one end thereof provided with a series of excavating buckets and a digging wheel frame mounted for vertical adjustments on the main frame, thereby to excavate at different depths, a sight rod on the main frame operatively connected to derive movement from vertical movement of the digging wheel frame, and means for correcting the sight rod inaccuracies due to vertical movements of the front 30 end portion of the main frame.

5. In a ditching machine having a main frame and a digging wheel at one end thereof provided with a series of excavating buckets and a digging wheel frame mounted for vertical adjustments on the main frame, thereby to excavate at different depths, a vertically movable grade indicator on the main frame, and means including a cable and sheave arrangement providing an operative connection between the grade indicator and the digging wheel frame for causing the indicator to move upwardly or downwardly in the same direction and to the same extent as the digging wheel frame, said indicator being positioned a substantial distance forwardly of the rear end of the main frame and in advance of the operator's seat.

6. In a self propelled ditching machine having a main frame, an operator's seat disposed forwardly of the rear end of the main frame, a digging wheel at one end of the main frame and a digging wheel frame mounted for vertical movements on said main frame, a sight rod mounted for vertical movements in front of the operator's seat to be conveniently observed therefrom, and mechanical means responsive to digging wheel frame movements for causing corresponding movement to the sight rod, thereby to enable the operator by observing the sight rod and comparing same with the usual grade stakes to determine proper positioning of the digging wheel.

7. In a self propelled ditching machine, a main frame, front and rear wheels on said main frame, upright elevator rails at the rear end of the main frame, a digging wheel frame mounted for vertical movement on said elevator rails, a digging wheel carried by said digging wheel frame, an upright bracket arm carried by the digging wheel frame in the region of said elevator rails, 70 75 a grade indicator mounted for vertical move-

ments forwardly on said main frame, an endless cable on which said grade indicator is mounted, sheaves over which said cable passes including a sheave on said bracket arm, sheaves on said elevator rails, and sheaves on said main frame whereby the vertical movements of said bracket arm imparts movement to said endless cable causing corresponding up or down movement of the sight rod.

8. In a self propelled ditching machine, a main frame, front and rear wheels on said main frame, upright elevator rails at the rear end of the main frame, a digging wheel frame mounted for vertical movement on said elevator rails, a digging wheel carried by said digging wheel frame, an upright bracket arm carried by the digging wheel frame in the region of said elevator rails, a grade indicator mounted for vertical movements forwardly on said main frame, an endless cable on which said grade indicator is mounted, sheaves over which said cable is trained including sheaves on said bracket arm and sheaves on said digging wheel frame spaced rearwardly from said bracket arm carried sheaves, an anchor for one end of the cable on said bracket arm and an anchor on the digging wheel frame for the other end of said cable, the cable strands passing from the sheaves on the bracket arm to the

sheaves on said digging wheel frame compensating for angular movements of said main frame, vertically spaced sheaves on said elevator rails and sheaves on the main frame, the arrangement being such that up and down movement of the bracket arm transmits like movement to the grade indicator, and resilient means for maintaining the cable taut.

9. In a ditching machine having a main frame 10 and a digging wheel at one end thereof provided with a series of excavating buckets and a digging wheel frame mounted for vertical adjustments on the main frame, thereby to excavate at different depths, a vertically movable grade indicator on the main frame, and means including a cable and sheave arrangement providing an operative connection between the grade indicator and the digging wheel frame for causing the indicator to move upwardly or downwardly in the same direction and to the same extent as the digging wheel frame, said cable and sheave arrangement also including a compensating device for correcting inaccuracies in the position of the grade indicator due to up or down movement of the front end of the main frame caused by encountering depressions or raised portions of the ground surface.

WILLIAM G. VAN VOORHIS.
